UNITED STATES PATENT OFFICE

2,684,233

FROTH FLOTATION APPARATUS

Pearson M. Payne, Denver, Colo.

Application December 7, 1951, Serial No. 260,480

11 Claims. (Cl. 261—93)

1

This invention relates to apparatus for the agitation and froth floatative separation of granular or comminuted materials, such as ores, and more particularly to agitating and froth flotation apparatus of the general type and operative organization disclosed in my application for Letters Patent of the United States filed on August 13, 1948, serial No. 44,118, now issued under date of December 11, 1951, as Patent No. 2,577,802, and has as an object to provide novel and improved means in combination and operative association with the apparatus of my said earlier patent effective to extend the utility, enhance the efficiency, and facilitate regulation and operative control thereof.

My earlier patent above identified discloses the operative association with a flotation cell or agitating compartment of agitating and air induction means in the form of a vertically-axised, rotatable impeller unit characterized by fixedly-associated, angularly-spaced, like rods or stiff whip elements diverging outwardly and downwardly in intersecting relation with the level of the material to be agitated and through the body of such material to termination in free ends spacedly adjacent the floor of the cell or compartment, and the improvements of the instant invention relate to means for effectively applying the agitations and air inductions incident to rotation of such an impeller to efficient use in the conditioning of materials introduced within the cell or compartment, to the selective froth floatative separation of such materials, to the recirculation of the cell or compartment contents to and through the influence of the impeller, and to the regulation and control of such operations.

With the foregoing and other objects in view, my invention consists in the construction, arrangement, and combination of elements as hereinafter set forth, pointed out in my claims, and illustrated by the accompanying drawings, in which—

Figure 1 is a side elevation, partly in vertical section, of a laboratory batch flotation machine embodying the disclosures of my earlier application as typically associated with the improvements hereinafter described. Figure 2 is a vertical section, on a relatively enlarged scale, taken axially through the cell and impeller organization of the apparatus shown in Figure 1. Figure 3 is a cross section taken substantially on the indicated line 3—3 of Figure 2. Figure 4 is a cross section taken substantially on the indicated line 4—4 of Figure 2. Figure 5 is a fragmentary, detail vertical section, on a further enlarged scale

and with portions broken away to conserve space, taken substantially axially of an altitudinally-adjustable mounting and support utilized in the organization according to Figure 1. Figure 6 is a detail cross section, on a relatively enlarged scale, taken substantially on the indicated line 6—6 of Figure 1. Figure 7 is a top plan view of an alternative embodiment and adaptation of the invention. Figure 8 is a vertical section taken substantially on the indicated line 8—8 of Figure 7. Figure 9 is a cross section, on a relatively enlarged scale, taken substantially on the indicated line 9—9 of Figure 8. Figure 10 is a fragmentary, detail section taken substantially on the indicated line 10—10 of Figure 9.

2
In the embodiment of the invention typified by Figures 1—6, inclusive, of the drawings, a froth flotation cell is conventionally represented as a relatively-deep, conveniently-cylindrical, open-top bowl 10 formed with a froth-overflow lip 11 cooperating with a notch in the upper margin of the bowl wall. The bowl 10 is shown as carried by and to upstand with its axis vertical from a base 12 which supports, as hereinafter more particularly described, an altitudinally-adjustable drive and operative mounting for an impeller shaft 13 coaxial with said bowl and rotatable about its axis in an operative disposition intersecting the plane of the bowl top rim. Fixed to and rotatable with the lower end of the shaft 13, an impeller assembly, comprising a plurality of like, stiff, rod elements 14 fixedly engaged at their upper ends in and with a collar 15 secured to the shaft 13 and correspondingly diverging outwardly and downwardly from said collar in a uniform angular spacing definitive of a hollow frustum of a cone, is mounted and disposed for rotation within the bowl 10 with the divergent free lower ends of the rods 14 well spaced from and to clear the bowl bottom and side wall areas and the collar 15 above the normal pulp level of the bowl to dispose said rods in normal intersecting relation with the surface of the bowl charge as indicated at L in Figure 2. To operatively mount and adjustably support the shaft 13 and its associated impeller assembly, a post 16 fixedly upstanding from the base 12 in axial parallelism with and at one side of the bowl 10 slidably engages within and reciprocably mounts a tubular member 17 fixedly related at its upper end with a right-angled arm 18 arranged to overhang the bowl 10 and a sleeve 19 on the free end of said arm 18 is arranged to rotatably accommodate and to be traversed by the shaft 13 in a coaxial relationship 50 of said sleeve, shaft, and the bowl 10. A bracket

28 adjustably engaged with the member 17 upper end in an extension laterally therefrom opposite to the arm 18 projection mounts an electric motor 21 with its shaft paralleling the shaft 13 so that coplanar pulleys 22 and 23 fixed respectively to the motor shaft upper end and to the end of the shaft 13 above the sleeve 19 and interlinked by a belt 24 may function as a drive for the shaft 13 and its impeller assembly powered by said motor 21. Selective altitudinal adjustment of 10 the member 17 and the elements carried thereby is provided through the agency of a rack 25 fixed longitudinally of the post 16 interiorly of said member, a gear 26 rotatable in ears 27 outstanding in spaced parallelism from said member and meshing with the rack 25 through an opening in the member wall, a handle 28 for the manual rotation of the gear 26, and a ratchet and detent arrangement 29 effective to hold the gear 26 in any adjusted relationship along the rack 25, 20 the adjusting means shown and described being capable of functioning in an obvious manner to elevate and lower the impeller assembly axially of the bowl 19 and to hold said assembly available and in condition for operation at any 25 position in its range of altitudinal adjustment.

All of the foregoing is but typical of organizations and arrangements utilizing the novel impeller assembly and operative relationships disclosed in my earlier Patent No. 2,577,802, and is herein illustrated and described as representative of known means and particular combinations wherewith and wherein my further improvements are of especial advantage, it being readily apparent that power rotation of the shaft 13 and 30 its impeller assembly with the rods 14 of the latter penetrating the body and intersecting the surface of a pulp charge within the bowl 19 will function to whip and agitate the pulp charge and to entrain air from above the charge surface 40 along and immediately behind the moving rods 14 for dissemination as bubbles within and throughout the agitated charge and for jet-like delivery from the rod free ends at appropriate speeds of rod translation.

Apparatus characterized by impellers of the type shown in my earlier Patent No. 2,577,802, and hereinabove described has successfully operated to effectively agitate and to thoroughly and satisfactorily aerate pulps of various natures and consistencies for selective froth flotation and for conditioning thereof, but factors pertinent to pulp recirculation, to the development of circulatory currents within the pulp, to scouring of the sediments from the cell bottom, to maintenance of a quiescent zone adjacent the froth bed, to the depth and location of the impeller vortex, and to regulation of the induced air volume, are significant to the operating efficiency of the particular impeller assembly shown and described and give practical occasion for the further improvements 50 of the present invention.

Primary to the organization and operation of the features characterizing the present invention, a hollow, frusto-conical shroud 30 is provided in a size and form to spacedly engage about and to house the major length of the impeller assembly and the orbit of impeller rod 14 revolution. As associated with the apparatus according to Figures 1-4, inclusive, of the drawings, the shroud 30 is provided with a coaxial, fixedly-related, tubular neck 31 extending from its lesser end for telescopic engagement with and about the lower end of the sleeve 19 in a tight frictional fit on, or other attachment to, the latter effective to mount the shroud 30 on and for alti- 60

tudinal adjustment with said sleeve in coaxial relation with the shaft 13 and associated impeller assembly and in a downwardly-flaring extension through the surface of the pulp charge within the bowl and into the body of the pulp charge such as will position the lower open end of the shroud somewhat above the plane common to the lower or free ends of the rods 14 and dispose the shroud conical wall in clearing relation about and outwardly from the impeller assembly rods 14 and their operative orbit, thus to permit free rotation of the impeller assembly interiorly of the shroud. Since the shroud 30 and its neck 31 fully house and enclose the impeller assembly elements extending above the surface of the pulp charge in the bowl, it is clear that rotation of the impeller assembly as so housed will be ineffectual to establish induction of air within and through the pulp charge unless provision is made for supply of air, or analogous gases, to said neck and the shroud lesser end, for which purpose a suitable flow line 32 equipped with a valve 33 leads from atmosphere, or from a supply of desired particular gas, to and opens at its delivery end through the neck 31. Thus, when the impeller assembly is rotating interiorly of the shroud 30, the amount of air, or other gas, consequently introduced and disseminated within the pulp charge may be controlled and regulated by means of valve 33 adjustment and the position of the vortex in the pulp surface incident to such impeller assembly rotation may be correspondingly lowered or elevated within the shroud relative to the normal pulp level in reaction to such valve manipulation.

Fixed to and outstanding laterally from and about the lower end of the shroud 30, a series of like, flat vanes 34 is arranged in a uniform angular spacing of the individual vane elements to dispose the latter as fixed baffles within and substantially across the space between the shroud lower end and the adjacent bowl wall. The vanes 34 are approximately rectangular in plan, are similarly fixed at their corresponding inner margins to the shroud lower end in a generally radial projection therewith so as to position their outer margins substantially parallel with the bowl side wall, extend vertically across the plane of the shroud open lower end to dispose their parallel upper and lower margins respectively above and below said plane and to position their said lower margins adjacent and in clearing relation above the floor of the bowl and in a common plane below that of the impeller rod 14 free ends, and are preferably, though not necessarily, similarly inclined to the vertical, substantially as shown. It is the function of the vanes 34 to modify and direct pulp currents and agitations developed by impeller assembly rotation in a manner and to a degree susceptible of regulation through variation in the number, relative size, particular disposition, and inclination of the said vanes in a given installation, the vane arrangement illustrated being obviously effective upon impeller-generated pulp outflow from the shroud lower end to interrupt and inhibit the development of pulp currents tending to swirl with the impeller circularly of the bowl, to direct pulp currents against and with scouring effect upon the bowl floor, to stimulate pulp agitation through the generation of uprise currents along the bowl walls and between the vanes, and to thoroughly commingle the agitated pulp with air or gas bubbles introduced along and delivered from the free ends of the rods 14. Enhancing the pulp-agitating and 70

bubble-disseminating effect of the vanes 34, holes 35 may be formed in and through said vanes in any number, particular size, and pattern deemed to be appropriate in a given practical application of the apparatus, and interruption and deflection of radially-directed pulp currents may be effectively had, when desired, through the provision of an annular band 36, of appropriate width, engaging and fixed to the outer margins of the vanes 34.

For maintenance of a pulp charge interiorly of the shroud 30 lower portion subject to action of the impeller assembly and to accommodate circulation and recirculation of the pulp through the influence of the impeller, the length of said shroud is interrupted well below the normal pulp level of the cell, and preferably a short distance above the upper margins of the vanes 34, by an annular throat 37 of operatively-suitable width axially of the shroud which extends entirely about the shroud in an orbit perpendicular to the shroud axis and divides said shroud into an upper portion carried by the neck 31 and a separate, lower skirt portion attached to and supported from said upper portion by suitable means, such as struts 38 bridging said throat 37 in angularly-spaced relation and fixedly end-engaged with the separated shroud portions, the upper end of the shroud lower skirt portion expediently being formed as a radially and outwardly directed annular flange 39 effective to stiffen the tubular shroud skirt and to direct inflow of pulp through the throat 37. With the impeller and shroud arrangement shown and described, rotation of the impeller assembly operates to exhaust pulp and intermingled air bubbles from the shroud interior through the open lower end of the shroud for agitation and uprise within the cell under the influence and direction of the vanes 34 and band 36, the material so exhausted from the shroud interior being continuously replaced by inflow of pulp through the throat 37 with consequent most thorough recirculation of the pulp and agitation thereof in intimate and repetitious exposure to the air or gas bubbles generated within the pulp by the impeller action.

In accordance with the principles of froth flotation, the air or gas bubbles generated within the cell rise through the pulp charge with the pulp particles to which they have become attached and collect on and above the pulp level of the cell as a froth bed removable over the lip 41 for segregation of the material levitated thereby, such uprise of the bubbles and the efficient collection thereof in and as a froth bed on the pulp surface being facilitated with advantage of separatory efficiency through damping out of turbulence and eddy currents in the upper levels of the pulp charge and the consequent provision of a quiescent pulp zone underlying the froth bed. For the purposes and to develop the effects just above noted, it is practical and convenient to provide a diffusing baffle 40 on and about the shroud 30 above the throat 37 in a generally horizontal disposition across the space between the shroud and the cell side wall, said baffle 40 preferably being in the form of a somewhat flattened frustoconical plate conformed in plan with the bowl 10 and of a size to slidably engage within said bowl, an opening centrally and through the lesser end of said plate sized and conformed to embrace the shroud 30 upper portion and to marginally engage said shroud portion immediately above the throat 37 for positioned support of the baffle thereon, holes 41 intersecting the baffle conical area in such size, number, and pattern as will adequately accommodate uprise

of air and gas bubbles therethrough, and an upturned lip 42 peripherally of the baffle plate facilitative of baffle plate introduction within, and adjustment thereof altitudinally of, the bowl 10.

5. With the baffle 40 positioned as shown and described, the turbulence and eddy currents generated by impeller assembly rotation are largely confined to the lower area of the pulp charge below said baffle and deflected away from disturbing effect upon the pulp charge area above the baffle, the air or gas bubbles approaching and impinging against the baffle passing through the holes 41 thereof by virtue of their tendency to uprise vertically through the pulp and completing such
10. uprise to the pulp surface through the relatively quiet upper area of the pulp charge with a minimum of collapse and loss of their particle charges; the comparatively undisturbed surface of the pulp charge facilitating development of the desired
15. froth bed in floating relation therewith.

In a structural arrangement and operative organization analogous to that hereinabove described, the improvements of the present invention are shown in Figures 7-10, inclusive, as associated

20. for practical use in and with a cell adapted to accomplish either froth floatation or conditioning treatment of a pulp. In the views last above noted, the cell 10' is shown as rectangular in plan, as formed with a floor inwardly and downwardly-sloped from each side of the cell to a horizontal floor area centrally and longitudinally of the cell, and as associated for continuous flow operation with a pulp feed box 43 arranged for input of pulp to the cell at and to one end of the cell
25. floor central area and for delivery of treated pulp through a hooded outflow orifice 44 to a succeeding cell 10'', all in accordance with known and conventional practice. The cell 10' is furnished with a rigid bridge 45 fixedly spanning its open top whereon the tubular sleeve 19 is positioned and supported with its axis vertical and centrally of the cell to dispose the shaft 13 with its associated impeller assembly of rods 14 and collar 15 in and for rotation relative to the cell in the manner
30. 40. and for the purposes of pulp agitation and air induction previously described. The motor is adjustably carried by the bridge 45 with its shaft vertical so that the pulleys 22 and 23 may engage the belt 24 for completion of a power drive to the
35. shaft 13 and impeller assembly as previously set forth. Structurally and functionally analogous to the shroud 30, a frusto-conical shroud 30' comprised of upper and lower portions separated by an annular throat 37' is supplied with fixedly-related stem members 46 engaging its exterior surface and bridging the throat 37' to interconnect the otherwise separate shroud 30' portions, and extensions of said members 46 beyond the lesser end of the shroud are arranged to parallel the
40. shroud axis and threaded for a distance adjacent their free ends, so that when said member extensions are engaged through holes in elements of the bridge 45 supporting the sleeve 19 and with nuts adjusted to bear against said bridge elements
45. 55. the shroud 30' is mounted in altitudinally-adjustable, coaxial relation with and to house the impeller assembly constituted by the rods 14. The shroud 30' is axially shorter than the impeller assembly and is of a size and conformation to
50. 60. accommodate the impeller for free rotation therewith when the said shroud is positioned to expose the collar 15 and rod 14 upper ends above its lesser end plane and to establish projection of the rod 14 free ends below its greater end plane,
65. 70. 75. the said lesser and greater ends of the shroud

being preferably stiffened and reinforced by means of annular flanges 39' outstanding radially therefrom and the shroud lesser end preferably being formed as an axially-short cylindrical band 47 upstanding in coaxial relation therefrom. At its lower end the shroud 30' carries fixedly-related vanes 34', each preferably intersected by a plurality of holes 35', in a radially-outstanding, angularly-spaced, preferably inclined arrangement structurally and functionally the same as that of the vanes 34 of the embodiment first described, and outer ends of the said vanes 34' close against and are encircled by an annular band 36' which may be operatively associated with and for altitudinal adjustment relative to the vanes by means of slotted ears 48 fixed to and extending inwardly from the band inner surface to conformably overlie certain of the vane outer ends in clampable association with bolts 49 engaged through the said vane ends and the slots of said ears.

When utilized for froth flotation purposes, the organization represented in Figures 7, 8, 9 and 10 operates to agitate, aerate, and recirculate the pulp in an obvious manner closely similar, except for regulation of air inflow to the impeller, to that characterizing operation of the first-described embodiment of the improvements. For such froth floatative operation of the apparatus, the level L of the cell pulp charge is established, through altitudinal adjustment of the shroud 30' or through regulation of pulp flow to and through the cell, or both, at a plane below that of the band 47 upper end, thereby to inhibit inflow of pulp to the shroud through its open upper end and to dispose said band 47 as a baffle upstanding through the froth bed to dam the latter away from entrainment within the pulp body, thus constituting the open throat 37' as the means accommodating inflow of pulp from the cell and to the shroud interior as the impeller acts to exhaust pulp from and through the lower end of the shroud, whereby to effectively recirculate the pulp in the lower area of the cell and to minimize the development of eddies and currents within the progressively more quiet pulp zones above said throat.

For thorough and repetitious agitation of the entire pulp charge, as in the conditioning of ore pulps in the presence of reagents, and the like, the apparatus represented in Figures 7, 8, 9 and 10 may be efficiently and advantageously utilized simply by closing the throat 37' of the shroud 30' and adjusting the level of the cell pulp charge, through regulation of pulp flow to and through the cell or by varying the altitudinal disposition of the shroud, to a relation with the shroud open upper end indicated at L' such as will submerge the shroud wholly within the pulp charge and establish a continuous feed of pulp to the shroud interior through the open collar 47 when and as the impeller is operating. Various expedients may be availed of for selectively closing the shroud throat 37', a convenient arrangement for such purpose being illustrated as comprising segmental skirt plates 50 adapted to close over the throat areas between the stem members 46 in engagement with positioning and supporting means, such as hooks 51 and latch studs 52, carried by the shroud.

Obviously, the baffle 40 may be utilized with the shroud 30' in the manner and for the purposes to which it is applied in association with the shroud 30, the shroud 30 may be open to atmosphere at its lesser end and provided with

closures for its throat 37, whereby to adapt it for use in the conditioning of the pulp, and the shroud 30' may be provided with a chamber at its upper end closed to atmosphere and furnished with a valved inlet, in the manner and for the purposes characterizing the like means associated with the shroud 30, all such relationships and reorganizations of the elements shown and described being clearly within the manifest scope and contemplation of the invention.

Since changes, variations, and modifications in the form, construction, and arrangement of the elements shown and described may be had without departing from the spirit of my invention, I wish to be understood as being limited solely by the scope of the appended claims, rather than by any details of the illustrative showing and foregoing description.

I claim as my invention:

1. The combination with an open-top cell adapted to contain ore pulp and a vertically-axisied, frusto-conical impeller assembly of angularly-spaced, divergent rods rotatable about its axis in agitating and aerating relation with the cell pulp charge with its lesser end uppermost, of a frusto-conical shroud non-rotatably fixed coaxially with and spacedly about the major length of said impeller with the shroud lower end upwardly adjacent the lower end of the impeller, vanes fixedly outstanding radially from and in angularly-spaced relation about the lower end of said shroud with their outer ends inwardly clearing the cell walls and their lower margins in a plane above the cell floor and below the lower end of the impeller assembly, and a throat circumferentially interrupting said shroud above said vanes for the circulation of pulp therethrough.

2. The combination with an open-top cell adapted to contain ore pulp and a vertically-axisied, frusto-conical impeller assembly of angularly-spaced, divergent rods rotatable about its axis in agitating and aerating relation with the cell pulp charge with its lesser end uppermost, of a frusto-conical shroud non-rotatably fixed coaxially with and spacedly about the major length of said impeller with the shroud lower end upwardly adjacent the lower end of the impeller, vanes fixedly outstanding radially from and in angularly-spaced relation about the lower end of said shroud with their outer ends inwardly clearing the cell walls and their lower margins in a plane above the cell floor and below the lower end of the impeller assembly, a throat circumferentially interrupting said shroud above said vanes for the circulation of pulp therethrough, a neck extension of the shroud upper end defining a chamber closed to atmosphere, and a valve-controlled inlet to said chamber above the pulp charge level.

3. The combination with an open-top cell adapted to contain ore pulp and a vertically-axisied, frusto-conical impeller assembly of angularly-spaced, divergent rods rotatable about its axis in agitating and aerating relation with the cell pulp charge with its lesser end uppermost, of a frusto-conical shroud non-rotatably fixed coaxially with and spacedly about the major length of said impeller with the shroud lower end upwardly adjacent the lower end of the impeller, vanes fixedly outstanding radially from and in angularly-spaced relation about the lower end of the shroud with their outer ends inwardly clearing the cell walls and their lower margins in a plane above the cell floor and below the

lower end of the impeller assembly, a throat circumferentially interrupting said shroud above said vanes for the circulation of pulp therethrough, and a baffle engaged with and exteriorly about said shroud immediately above said throat in spacedly-overhanging relation with said vanes.

4. The combination with an open-top cell adapted to contain ore pulp and a vertically-axised, frusto-conical impeller assembly of angularly-spaced, divergent rods rotatable about its axis in agitating and aerating relation with the cell pulp charge with its lesser end uppermost, of a frusto-conical shroud non-rotatably fixed coaxially with and spacedly about the major length of said impeller with the shroud lower end upwardly adjacent the lower end of the impeller, vanes fixedly outstanding radially from and in angularly-spaced relation about the lower end of said shroud with their outer ends inwardly clearing the cell walls and their lower margins in a plane above the cell floor and below the lower end of the impeller assembly, a throat circumferentially interrupting said shroud above said vanes for the circulation of pulp therethrough, a neck extension of the shroud upper end defining a chamber closed to atmosphere, a valve-controlled inlet to said chamber above the pulp charge level, and a baffle engaged with an exteriorly about said shroud immediately above said throat in spacedly-overhanging relation with said vanes.

5. The combination with an open-top cell adapted to contain ore pulp and a vertically-axised, frusto-conical impeller assembly of angularly-spaced, divergent rods rotatable about its axis in agitating and aerating relation with the cell pulp charge with its lesser end uppermost, of a frusto-conical shroud non-rotatably fixed and mounted for altitudinal adjustment coaxially with and spacedly about the major length of said impeller with the shroud lower end at all times upwardly adjacent the lower end of the impeller, vanes fixedly outstanding radially from and in angularly-spaced relation about the lower end of said shroud with their outer ends inwardly clearing the cell walls and their lower margins in a plane above the cell floor and below the lower end of the impeller assembly, a throat circumferentially interrupting said shroud above said vanes for the circulation of pulp therethrough, an annular collar concentrically upstanding from the shroud lesser end and altitudinally adjustable with the shroud between extension above and submergence below the pulp charge level, and means for selectively closing said throat.

6. In apparatus of the character described having an open-top cell adapted to contain ore pulp and a vertically-axised impeller assembly of angularly-spaced, divergent rods rotatable about its axis in agitating and aerating relation with the cell pulp charge with its lesser end uppermost, a frusto-conical shroud non-rotatably fixed coaxially with and spacedly about the major length of said impeller with the shroud lower end upwardly adjacent the lower end of the impeller, vanes fixedly outstanding from and in angularly-spaced relation about the lower end of the shroud with their outer ends inwardly clearing the cell walls and their lower margins in a plane above the cell floor and below the lower end of the impeller assembly, and a throat circumferentially interrupting said shroud above

the vanes to provide a pulp recirculation passage to the shroud interior.

7. In apparatus of the character described having an open-top cell adapted to contain ore pulp and a vertically-axised impeller assembly of angularly-spaced, divergent rods rotatable about its axis in agitating and aerating relation with the cell pulp charge with its lesser end uppermost, a frusto-conical shroud non-rotatably fixed coaxially with and spacedly about the major length of said impeller with the shroud lower end upwardly adjacent the lower end of the impeller, vanes fixedly outstanding from and in angularly-spaced relation about the lower end of the shroud with their outer ends inwardly clearing the cell walls and their lower margins in a plane above the cell floor and below the lower end of the impeller assembly, a throat circumferentially intersecting said shroud above the vanes to provide a pulp recirculation passage to the shroud interior, a neck extension of the shroud upper end defining a chamber closed to atmosphere, and a valve-controlled inlet communicating with said chamber above the cell pulp charge level.

8. In apparatus of the character described having an open-top cell adapted to contain ore pulp and a vertically-axised impeller assembly of angularly-spaced, divergent rods rotatable about its axis in agitating and aerating relation with the cell pulp charge with its lesser end uppermost, a frusto-conical shroud non-rotatably fixed coaxially with and spacedly about the major length of said impeller with the shroud lower end upwardly adjacent the lower end of the impeller, vanes fixedly outstanding from and in angularly-spaced relation about the lower end of the shroud with their outer ends inwardly clearing the cell walls and their lower margins in a plane above the cell floor and below the lower end of the impeller assembly, a throat circumferentially intersecting said shroud above the vanes to provide a pulp recirculation passage to the shroud interior, and a baffle engaging with and exteriorly about said shroud immediately above said throat in spacedly-overhanging relation with said vanes.

9. In apparatus of the character described having an open-top cell adapted to contain ore pulp and a vertically-axised impeller assembly of angularly-spaced, divergent rods rotatable about its axis in agitating and aerating relation with the cell pulp charge with its lesser end uppermost, a frusto-conical shroud non-rotatably fixed coaxially with and spacedly about the major length of said impeller with the shroud lower end upwardly adjacent the lower end of the impeller, vanes fixedly outstanding from and in angularly-spaced relation about the lower end of the shroud with their outer ends inwardly clearing the cell walls and their lower margins in a plane above the cell floor and below the lower end of the impeller assembly, a throat circumferentially intersecting said shroud above the vanes to provide a pulp recirculation passage to the shroud interior, a baffle engaging with and exteriorly about said shroud immediately above said throat in spacedly-overhanging relation with said vanes, and apertures extensively interrupting said baffle and said vanes for pulp circulation therethrough.

10. In apparatus of the character described having an open-top cell adapted to contain ore pulp and a vertically-axised impeller assembly of angularly-spaced, divergent rods rotatable about its axis in agitating and aerating relation with the cell pulp charge with its lesser end uppermost, a frusto-conical shroud non-rotatably fixed

11

coaxially with and spacedly about the major length of said impeller with the shroud lower end upwardly adjacent the lower end of the impeller, vanes fixedly outstanding from and in angularly-spaced relation about the lower end of the shroud with their outer ends inwardly clearing the cell walls and their lower margins in a plane above the cell floor and below the lower end of the impeller assembly, a throat circumferentially intersecting said shroud above the vanes to provide a pulp recirculation passage to the shroud interior, a neck extension of the shroud upper end defining a chamber closed to atmosphere, a valve-controlled inlet communicating with said chamber above the cell pulp charge level, and a baffle engaging with and exteriorly about said shroud immediately above said throat in spacedly-overhanging relation with said vanes.

11. In apparatus of the character described having an open-top cell adapted to contain ore pulp and a vertically-axised impeller assembly of angularly-spaced, divergent rods rotatable about its axis in agitating and aerating relation with the cell pulp charge with its lesser end uppermost, a frusto-conical shroud non-rotatably fixed coaxially with and spacedly about the

10
